Primary Examiner — Susan Moon Lee(74) *Attorney, Agent, or Firm* — David R. Conklin;
 Kirton McConkie(57) **CLAIM**

The ornamental design for a three-dimensional gameboard, as shown and described.

DESCRIPTION

FIG. 1 is a top, front and left side perspective view of the three-dimensional gameboard in an extended configuration with horizontal rod pieces in place.

FIG. 2 is a front elevation view thereof.

FIG. 3 is a back elevation view thereof.

FIG. 4 is a left side elevation view thereof.

FIG. 5 is a right side elevation view thereof.

FIG. 6 is a top plan view thereof;

FIG. 7 is a bottom plan view thereof;

FIG. 8 is a top, front and left side perspective view of the three-dimensional gameboard in a retracted configuration with horizontal rod pieces removed.

FIG. 9 is a front elevation view thereof.

FIG. 10 is a back elevation view thereof.

FIG. 11 is a left side elevation view thereof.

FIG. 12 is a right side elevation view thereof.

FIG. 13 is a top plan view thereof; and,

FIG. 14 is a bottom plan view thereof.

The broken lines depict environment for illustrative purposes only and form no part of the claimed design.
